CLOSURE FOR TRUCK TANKS AND THE LIKE

Carlyle H. Scott, Forest Hills, and Paul H. Scott, Flushing, N. Y., assignors to The Safety Tank Truck Corporation, New York, N. Y., a corporation of New York

Application May 25, 1940, Serial No. 337,270.

7 Claims. (Cl. 292—336)

This invention relates generally to manhole closures for tanks of the type mounted on trucks and adapted for receiving and dispensing inflammable liquids, such as gasoline or fuel oil. More particularly it relates to a locking arrangement whereby covers, even of large size, may be securely held in place over a manhole opening, affording a vapor-tight closure, and security against accidental opening. More specifically, it relates to a locking device of the character mentioned in which a latch tends normally and automatically to assume a position in which it holds the cover in place over the manhole opening, and it which the latch may be brought manually into a position in which it holds the latch in a retracted position, ready however, when released, to act automatically.

While our invention has been described in its application to truck tanks, it will be understood that, particularly as to certain phases thereof, it may have other applications.

In closures of the character mentioned, great difficulty has been experienced in obtaining secure locking and vapor-tight engagement of the cover with its seat. While the known constructions function satisfactorily when applied to manholes of small diameter (about six inches or less), such is not the case where larger diameters are in question. Since it is usually desired that the manhole be of a size large enough to admit a man into the tank, for purposes of inspection or repair, it will be readily understood that such known constructions may be stated to be unsatisfactory.

It is the general object of our invention to provide a simple, effective and inexpensive construction in a manhole cover and closure means therefor, that will have none of the disadvantages of the constructions heretofore known and will provide a secure vapor-proof closure for manholes, even of large size.

It is among the more particular objects of our invention to provide, in a manhole cover closure, a latching arrangement that, when left free, will automatically move into a locking position, and further to provide manually operated means for opening such a closure, to provide means for setting the automatic latching arrangement whenever the cover is opened, and to provide means for releasing the automatic latching arrangement whenever the closure is moved into its closing position.

To attain these objects and such further objects as may appear herein or be hereinafter pointed out, we make reference to the accom-

panying drawings, forming a part hereof, in which

Figure 1 is a plan view of one embodiment of our invention;

Figure 2 is a longitudinal sectional view through the embodiment of Figure 1;

Figure 3 is an end elevational view of the embodiment of Figure 1 as viewed from the left of said figure;

Figure 4 is an end elevational view of the embodiment of Figure 1 as viewed from the right of said figure;

Figure 5 is a fragmentary view similar to Figure 2, but on a reduced scale, and shows the parts as they appear while being moved so as to open the manhole cover;

Figure 6 is a view similar to Figure 5 but showing the parts in a further successive stage of opening the cover;

Figure 7 is a fragmentary view, similar to Figure 5, showing the parts as they appear when the cover is free to move into its fully opened position;

Figure 8 is a view similar to Figure 2, but in a reduced scale, of a second embodiment of our invention;

Figure 9 is a view similar to Figure 8, but showing the cover partly opened;

Figure 10 is a fragmentary plan view of the embodiment of Figure 8, with the parts in the position of Figure 9.

Before proceeding to a detailed description of our invention, we will premise that it comprises generally a manhole construction provided with an opening, a cover for closing the opening, and a frame for carrying the cover, the frame being hingedly mounted on the tank and being yieldably and resiliently connected to the cover. A latch is carried on the frame, and this latch is normally urged into locking engagement with a strike mounted in fixed relation to the tank. A handle is pivotally carried by the frame. When said handle is raised it retracts the latch, and the cover can be opened, while at the same time a back latch or trigger holds the handle so that the latch remains in its retracted position.

When the cover is moved into its closing position, the said back latch will be operated automatically to release the latch, which flies automatically into its locking position and locks the cover in place. The handle, which forms an element of a toggle link system, at the same time moves into a dead center position.

Two embodiments of our invention have been disclosed. In the first, the cover must be

"slammed" into place while closing, but it is opened by means of the handle. In the second embodiment, the handle may be used to manually and gradually move the cover into its closed position and it is also opened manually.

By way of illustration we have shown two embodiments of our invention. It will, however, be understood that these embodiments are illustrative merely and are only examples intended to explain the principles of our invention, without exhausting all of the possible variations and embodiments thereof.

Referring now to the drawings in detail, first of all to Figures 1 to 7, inclusive, in which the first embodiment of our invention is illustrated, it will be observed that we show a plate 20 mounted on a flanged rim 21, extending upwardly from a tank and provided with a flange 22 on which the plate 20 seats. A gasket 23 is interposed between the plate 20 and the flange 22 for the obvious purpose of providing a vapor-tight closure.

The plate 20 may be secured in place in any suitable or preferred manner as by bolts 24. The plate is provided with an opening 25 through which access may be had to the tank for filling or for entering the same for purposes of inspection or repair as is well understood. A cover 26 is adapted to seat over the opening 25. A gasket 27 is shown interposed between the cover 26 and a seat 27a provided on the plate 20 and surrounding the opening 25, and thereby a vapor-proof construction is provided.

Pivoted mounted on the plate 20 is a frame 28. This frame comprises two laterally spaced bars 29 and 30 connected at one end by a pin 31 and at their other ends by pin 32. A pin 33 is shown as passing through lugs 34 and 35 projecting upwardly from the plate 20 and this pin passes through the ends 36 and 37 of the bars 29 and 30, whereby it will be observed that the frame 28 may pivot about the said pin 33. Projecting laterally from the bar 29 is a pair of lugs 38 and 39, and similar lugs 40 and 41 are provided on the bar 30. Each of these lugs is provided with an opening 42 through which extends a pin 43 having one end secured at a bottom of the pocket 44 provided in the cover 26. A coil spring 45 is shown seated in each pocket 44 surrounding the pin 43 and serves to urge the cover 26 away from the frame 28. In order to maintain the connection between the cover 26 and the frame 28, the upper end of each pin 43 is shown as carrying a pair of nuts 46.

It will be observed that the cover 26 is shown as provided with four pockets 44, each corresponding to and registering with one of the lugs 38, 39, 40 and 41, and thereby the cover 26 is hung from the frame 28 at four symmetrically distributed points, and when the frame 28 is lowered into the position shown in Figure 2, it will press the cover 26 securely into place through the action of spring 45.

Pivoted mounted on a pin 47 at the free end of the frame 28 is a latch 48 provided with a pair of forked arms 49 between the outer ends of which passes a pin 50 on which is mounted a roller 51 which is adapted when the cover is in its closed position, to move underneath a strike 52 in a form of a hook having a nose or end portion 53, the inner surface of which is provided with a guideway or cam surface 54, shown as curved upwardly (see 55) so as to gradually guide the roller 51 into place adjacent the bight portion of the hook.

A torsion spring 56 is shown as engaging the arms 49 with its bight portion 57 and the pin 50 with its end portion 58, and it is so tensioned that it tends to drive the roller 51 away from the pin 50 and into locking position within the hook 52. A lever 59 is pivotally mounted on the frame 28. The lever 59 is adapted to be grasped by the hand for a purpose that will be herein-after explained.

10 Its pivot comprises a pair of spaced lug portions 59a at one end thereof, through which passes a pin 60 which is seated in the bars 29 and 30 of the frame 28 and adjacent to the pin 33 about which said frame pivots. A link 61 is shown pivoted at one end to a lug 62 projecting downwardly from the lever 59 as shown at 63, at an intermediate point thereof and pivoted at its other end to the latch 48 as shown at 64. It will be understood that as the lever 59 is raised, by 15 movement about the pivot, from its position in Figure 2, that the dead center position of the toggle formed by the lever 59 and the link 61 with the pivot points 63 and 64, will be broken, and the latch 48 will be moved against the resistance of torsion spring 56, toward the left. 20 The pivot point 63 is so positioned that adequate leverage is provided to effect such movement of the latch against the resistance of spring 56. It will be observed that because of the dead center position of the toggle arrangement as shown in Figure 2 the latch is securely held in its lock position as long as the lever 59 is in its position as shown in Figure 2.

A back latch or trigger arrangement is provided for the purpose of holding the lever in such a position that the latch is prevented from moving into its locking position. This arrangement may comprise a trigger or back latch 65 pivotally mounted on the pin 33 between the lugs 36 and 37 of the frame 28.

The trigger is provided with two notches 66 and 67 within which is adapted to seat a roller 68 carried on a pin 69 mounted on a pair of arms 70 projecting from the lever 59 at the pivoted portions thereof. Whenever the roller 68 seats in one of the notches 66 or 67 the lever 59 is locked relatively to said frame. This locking is effected by a spring 71 mounted on the pin 32 and so disposed and tensioned that it bears down on the trigger 65 so as to cause it to move downwardly as shown in Figure 2. The functioning of these parts will be better understood after the description of operation.

The trigger 65 is further provided with a nose portion 72 which serves to release or trip the trigger as will be more clear as the operation of the device is more fully understood.

The detailed description may be completed by mentioning a lug 73 provided on the frame 28 and serving as a stop to maintain the cover in substantially upright position when the cover is open, and by mention of an arrangement 74 whereby the length of the link 61 may be adjusted to secure proper functioning of the device.

65 With the aid of the foregoing description of the parts of our latching arrangement, its operation will be readily understood.

Beginning with the parts as shown in the position of Figure 2, an attendant desiring to open the cover will grasp the lever 59 and will raise it into the position indicated in Figure 5.

The effects of this raising of the handle will be two-fold. First of all, the link 61 will pull the latch 48 with its roller 51 toward the left, 70 thereby tensioning the spring 56 and the roller

51 will travel along the cam surface 55 into the position shown in Figure 5. The second effect will be a movement of the arms 70 and the roller 68 out of the notch 67 and into the notches 66 of the trigger 65, this being effected because the trigger 65 always tends to move downward about the pivot 3, owing to the action of the spring 71.

A continued raising of the lever 59 will result in an emergence of the roller 51 from the hook shaped strike 52 and seating of the roller 68 into the notch 66 of the trigger 65. In this position the parts are locked together and the spring 56 is held under tension and prevented from moving the latch by the action of trigger 65. It will be observed that the pressure on the roller is so directed against the pin 33, and the surfaces of the notch 66 are so disposed that the trigger cannot move. As a result, therefore, of moving the lever 59 up, the frame 28 rises and on continued movement will pass through the position shown in Figure 7 and into a position in which the lugs 73 of the frame engage the plate 20. This marks the limit full opening position of the cover. In order to close the cover the attendant simply moves the entire cover structure while it is in its locked position of Figures 6 and 7 by giving it a push or slam in the appropriate direction so as to close the cover. The effect of this movement will be a passing of the cover structure from the position in Figure 7 into the position of Figure 6 in which the lugs 72 of the trigger 65 will strike the plate 20 and substantially at the same time the roller 51 of the latch will engage the extreme end of the hook-shaped strike 52. The parts are so related that the roller 51 will be caused to move slightly to the left as shown in Figure 6, thereby removing the effect of the tension of the spring 56 from the trigger parts. The portion 72 of the trigger 65 will be held against further downward movement while movement of the lever 59 will cause the roller 68 to move out of the notch 66.

The position of the parts just described may be seen in Figure 5. As the roller 68 moves out of the notch 66 it releases the lever 59 from its locked position and the spring 56 is released and thereby snaps the roller 51 into its locked position as shown in Figure 2, drawing with it the handle 59. The roller 68 in the meantime has seated itself in the notch 67 and the lever 59 and the link 61 are in the dead center position indicated in Figure 2. The function of the inclined cam surface 54 on the strike 52 in gradually guiding the roller downward will be readily understood. It effects a gradual increase of the pressure on the cover 26 which becomes a maximum as the extreme right hand position of the roller 51, as shown in Figure 2, is reached.

In order to secure proper functioning of the parts, it is important that the trigger 65 be suitably contoured and the link 61 be suitably adjusted as to length.

It is to be observed that in the embodiment just described, it is not feasible to close the cover gradually by slow manipulation of the lever 59. This is because the spring 56, which must of necessity be of sufficient strength to secure the proper pressure on the cover, offers too great resistance to such slow manual movement, since a limited movement of the roller 51 from the position shown in Figure 6 is necessary in order to release the trigger 65. On the other hand, also, the end of the hook shaped strike 52 must extend to a sufficient distance to properly set the spring 56 on the upward or opening movement of the

cover to properly set the spring 56 in preparation for its automatic movement when the cover is closed.

In Figures 8, 9 and 10 we have shown a construction in which a gradual closing of the cover may be effected by manipulating the lever 59. In these figures, in order to avoid repetition, parts corresponding to similar parts of the first embodiment, have been designed by the same numerals. However, these numerals have been primed. The only constructional distinction between this embodiment and the first embodiment is the provision of an arched portion 80 in the lever 59 so as to provide a space into which the fingers of a hand may be safely inserted without danger of being crushed by adjacent parts. The strike 52' is further provided with a small dog 81 pivoted at 82 to the nose portion of the strike 52'.

The action of the dog 81 will be understood from an inspection of Figures 8 and 9. Starting with the position of Figure 8, as the lever 80 is raised the roller 51' will travel along the cam surface 55' until the position of Figure 9 is reached in which the roller 51' engages the projecting nose portion 83 of the dog 81. The dog is prevented from moving away from this position because its end 84 (inner end) is forced against the portion 85 of the strike 52' and thereby said nose portion 83 offers the obstruction requisite to a proper setting of the spring 56'.

Assuming now that the cover has been fully opened, the operator will grasp the lever 59' at its raised portion 80 and will gradually move the cover down. As it will move down the roller 51' will strike the nose 83 of the dog 81 but the latter will offer no resistance. Instead, it will move down therewith, and offer only a very slight resistance to the manual closing of the cover. The function of the parts thereafter is as described in connection with the first embodiment, the latch 48' being released so that the roller 51' moves into the locking engagement with the strike 52'.

It will be understood that we do not intend to limit ourselves to the exact combination of parts herein disclosed and that these parts may be combined in other relations than those shown.

While we have herein disclosed two illustrative embodiments of our invention, it will be understood that the same may be embodied in many other forms as will be obvious to those skilled in the art, without departing from the spirit thereof, and that the disclosure herein is by way of illustration merely, and is not to be interpreted in a limiting sense, and that we do not limit ourselves other than as called for by the language of the appended claims.

Having thus described our invention and illustrated its use, what we claim as new and desire to secure by Letters Patent is:

1. In a filling structure for truck tanks, having a base plate, a frame pivotally mounted on said base plate, a strike carried by said base plate, said strike being in the form of a hook having the inner surface of its end portion disposed substantially horizontally but gradually curving upwardly at the tip, a latch therefor carried by said frame, including resilient yieldable means for maintaining said latch in engagement with the strike when the frame is moved down, a locking lever pivotally mounted adjacent one side of said frame, means interconnecting said latch and said locking lever and adapted when angled relatively to said frame, to move said latch out of engage-

ment with the strike and to tension said resilient means operative on said latch, trigger means adjacent the other side of said frame for holding said locking lever in said angled position in which said resilient means is tensioned, and means for tripping said trigger means and releasing the latch when said frame is moved down so that the latch engages said strike.

2. In a filling structure for truck tanks, having a manhole and a closure for said manhole latching means for holding said closure in place over the manhole, said means comprising an arrangement for automatically locking said closure in place over the manhole, when released to fall by gravity into closing position, means on one side of said closure for holding said arrangement in an unlatching position, and means on the opposite side of said closure for bringing said arrangement from its latching to its unlatching position, said means comprising a toggle link system adapted to assume a dead center position when said locking arrangement is in its locking position and said means further comprising a member for breaking said dead center.

3. In a filling structure for truck tanks, having a manhole and a closure for said manhole means for holding said closure in place over the manhole, said means comprising an arrangement for automatically locking said closure in place over the manhole, when released to fall by gravity into closing position, means on one side of said closure for holding said arrangement in an unlatching position, and means on the opposite side of said closure for bringing said arrangement from its latching to its unlatching position, said means comprising a pivoted lever, connections between said lever and said locking means whereby when the lever is moved into a predetermined position said locking means will move into an unlatching position, and said holding means being operative to hold said lever in said predetermined position.

4. In a filling structure for truck tanks, having a manhole and a closure for said manhole latching means for holding said closure in place over the manhole, said means comprising an arrangement for automatically locking said closure in place over the manhole, when released, means on one side of said closure for holding said arrangement in an unlatching position, and means on the opposite side of said closure for bringing said arrangement from its latching to its un-

latching position, said means comprising a pivoted lever, connections between said lever and said locking means whereby when the lever is moved into a predetermined position said locking means will move into an unlatching position, and said holding means being operative to hold said lever in said predetermined position, and means for releasing said holding means and thereby said locking arrangement when said closure is brought into place over the manhole.

5. In a manhole closure, having a cover, automatic latch therefor comprising means for normally assuming a position in which it locks the cover in place, means on one side of said cover for moving said latch means into an inoperative position and setting it for automatic action whenever the cover is opened, and means on the opposite side of said cover for releasing said last-named means whenever the cover is moved into its closing position.

6. In a manhole closure having a cover, an automatic latch therefor comprising in combination, means for causing said latch to assume a position in which the latch locks the cover in place, means on one side of said cover for moving said latch into an inoperative position and setting the latch for automatic action whenever the cover is opened, and means operative when the cover engages the manhole wall for releasing said latch whenever the cover is moved into its closing position.

7. In a filling structure for truck tanks, the combination comprising a manhole frame, a strike adjacent one side of said frame and a closure for said frame pivotally mounted on said frame opposite to said strike, a strike engaging portion pivotally mounted upon said closure and movable into latching position by resiliently yieldable means, means for withdrawing said strike engaging portion from engagement with said strike upon movement opening said closure, and means for holding said strike engaging portion in unlatching position, setting said latch automatic action whenever the closure is moved to the open position, said means for holding said portion having an element disposed to engage a fixed part on said frame for releasing said strike engaging portion whenever the closure is moved into its closing position.
